UNITED STATES PATENT OFFICE.

CHARLES F. SMYTH, OF NEW HAVEN, CONNECTICUT, ASSIGNOR TO CONNECTICUT AIRCRAFT COMPANY, OF NEW HAVEN, CONNECTICUT, A CORPORATION OF CONNECTICUT.

INFLATABLE FABRIC BOAT AND BED OR CUSHION.

1,392,533.

Specification of Letters Patent.

Patented Oct. 4, 1921.

Application filed July 16, 1920. Serial No. 396,794.

To all whom it may concern:

Be it known that I, CHARLES F. SMYTH, a citizen of the United States, residing at New Haven, in the county of New Haven and State of Connecticut, have invented new and useful Improvements in Inflatable Fabric Boats and Beds or Cushions, of which the following is a specification.

This invention relates to a combination boat and bed or cushion, and particularly to an inflatable fabric device of this character of the readily portable type, one object of the invention being to provide a simple, strong, durable and comparatively inexpensive construction of combined boat and bed or cushion which in its use as a boat may be conveniently propelled by oars or the like over the surface of the water.

A further object of the invention is to provide an inflatable combination fabric boat and bed or cushion which is capable of carrying one or more passengers, of being quickly inflated for use and of being deflated and folded in compact form for storage or transportation, and which is provided with a plurality of air compartments to insure a high degree of buoyancy and safety under varying conditions of service.

A still further object of the invention is to provide a simple type of light weight combined portable boat and bed or cushion for the use of hunters, trappers, sportsmen, fishermen, campers, and others, which is reversible for use as a pneumatic pad or mattress to furnish a comfortable camp-bed or lounge or seat cushion, and which is also adapted for use as a float and pleasure craft at bathing beaches and similar resorts.

A still further object of the invention is to provide a simple type of light weight combination portable boat and bed or cushion which is reversible from boat service position for use as a pneumatic bed or cushion, thus furnishing a combined boat and bed or lounge or seat cushion of great convenience and value for the use of hunters, trappers, sportsmen, fishermen, and others camping out or engaged in like outdoor diversions.

A still further object of the invention is to provide a pneumatic boat which is adapted for use as a float and pleasure craft at bathing beaches and similar resorts.

A still further object of the invention is to provide simple and effective means for

holding the device folded and enabling it to be carried in a ready and convenient manner.

A still further object of the invention is to provide means for rendering the flexible bottom of the boat temporarily rigid so that a hunter or fisherman may conveniently stand upright in the craft when desired.

The invention consists of the features of construction, combination and arrangement of parts, hereinafter fully described and claimed, reference being had to the accompanying drawings, in which:

Figure 1 is a perspective view of an inflatable combined fabric boat and bed lounge or cushion constructed in accordance with my invention.

Fig. 2 is a top plan view of the same.

Fig. 3 is a central vertical transverse section through the device.

Fig. 4 is a view of the device as reversed for use as a pneumatic bed, lounge or the like.

Fig. 5 is a perspective view of one of the flexible partitions *per se*.

Figs. 6 and 7 are respectively views of the device as it appears when partly folded and as completely folded for storage or transportation.

Fig. 8 is a plan view showing the use of a rigid platform in connection with the craft.

Fig. 9 is a view of the invention as embodied in a small one-man type of combination boat and cushion.

In the practical embodiment of the invention as shown in Figs. 1 to 8, inclusive, I provide a combined boat and bed or cushion which is generally of oblong rectangular form in plan, and includes an outer inflatable frame comprising the hollow cylindrical side portions or floats 2 and the hollow cylindrical end portions or floats 3. These portions or floats 2 and 3 are made of a rubberized or other suitable flexible waterproof fabric, and are adapted to collapse into flat or substantially flat form and to be inflated into substantially cylindrical form. Each cylindrical portion 2 and 3 may be formed of a strip of fabric having its longitudinal edges directed inwardly and overlapped and suitably united, as indicated at 4, along the inner side of the cylinder. The cylinders 2 and 3 may be united at their adjacent ends in any suitable manner, as by having their end edges meet at a suitable angle at the corners

of the frame and united by suitable seams 5, the end portions of the cylinders 3 being preferably united in such manner as to be in open communication with each other.

- 5 The bottom 6 of the boat is formed of a strip of waterproof fabric which is disposed within the space bounded by the pneumatic frame formed by the cylindrical sides and ends 2 and 3, and is disposed at a point below the horizontal centers of the floats and adjacent to but slightly above the lower surfaces of such floats when the latter are completely inflated. The arrangement is thus such that when the craft is fully inflated and afloat and in its normal upright position for use as a boat, the bottom 6 may lie slightly above the submerged bases of the cylinders or floats, and thus decrease the depth of submergence and diminish resistance in the travel of the craft. The arrangement of the bottom 6 is also such as to form a cabin or compartment of some depth and surrounded by the unsubmerged upper portions of the hollow cylinders for 25 the reception of the occupant or occupants of the craft, such submerged upper portions of the cylinders providing a comparatively deep gunwale entirely around the cabin or compartment and of a sufficient height 30 above the level of the water to prevent waves from dashing over in ordinary weather. In such use one of the cylinders 3 will also form a back rest of adequate depth to comfortably support the back of the 35 operator when seated in the compartment and engaged in rowing, fishing or other occupations. The arrangement of the bottom 6 between the horizontal center and bottom surface of the float frame is also of advantage in adapting the device to be used as a 40 pneumatic bed or cushion. In such use the device is simply reversed or turned over, bottom side uppermost, in which position the flexible bottom 6 will lie above the horizontal center of the pneumatic frame and provide a shallow bedstead with a flexible bottom or mattress yieldingly supported by the pneumatic cylinders having their normally upper surfaces resting on the floor or 45 ground. When thus arranged the side and end cylinders will form the sides and end portions of an exceedingly comfortable bedstead and the end cylinders will project sufficiently so that either one may serve as 50 a soft and yielding pillow or head-rest, the surface of which will not lie at an objectionable elevation above the level of the bed bottom 6.
- 55 The bottom 6 is of a form to extend around the inner surfaces of the cylinders 2 and 3, and its marginal edges 7 are preferably turned upward at an angle along the inner sides of said cylinders in alignment with the seams 4 and are stitched or otherwise suitably secured to said cylinders. For 60 the purpose of reinforcing the device along the corner seams 5 reinforcing strips 8 are extended over such seams and stitched or cemented or both stitched and cemented to the cylinders. Reinforcing strips or tapes 70 9 of suitable waterproof fabric also extend around the edges of the bottom 6 and overlap the same and the adjacent portions of the cylinders 2 and 3 above and below the bottom 6, and are stitched or cemented or both stitched and cemented to the bottom and cylinders. Stays 10' are also similarly secured at the points of junction of the corners of the cylinders 2 and 3 and the bottom 6 to strengthen and reinforce the adjacent portions of such elements at these points. The stays increase the strength and durability of the parts of the combination boat and bed structure at the points where they are applied and also cover the seams 80 to reduce liability of leakage of air from the cylinders or the entrance of water thereto, and by the use of a waterproof cement the connections along the joints or seams may be made absolutely air and water 85 tight.
- 90 The air chambers formed by the cylinders 2 and 3 are sub-divided into compartments by flexible partitions 10. Each of these partitions 10 consists of a substantially 95 cone-shaped flexible rubber or fabric body having at its base or widest portion a cylindrical flange 11 secured to the inner surface of the cylinder in which it is disposed. These partitions are preferably arranged 100 about midway of the length of the respective cylinders 2 and 3, thus sub-dividing each cylinder so as to form with the adjoining portion of an adjacent cylinder an air compartment, such air compartments being 105 closed against communication with each other. By this means a plurality of compartments are provided for holding air, so that in the event of damage to the craft and leakage of air from any compartment 110 the buoyancy furnished by the inflation of the remaining compartment or compartments will keep the craft afloat. A check-valved inflation tube 12 is provided for communication with each air compartment so 115 that the cylinders or floats may be readily and quickly inflated. These valved tubes also allow the cylinders or floats to be quickly deflated so that the boat may be collapsed in a substantially flat condition 120 and folded for ready and convenient storage and transportation. By making the partitions of substantially conical form they are adapted to readily fold when the cylinders are collapsed so that the device 125 may be easily folded and packed, as herein-after described. Such form of the partitions also allows the fabric of which the cylinders are formed to stretch without placing tensional strains on the partitions. 130

The device when disposed for use as a boat, as shown particularly in Figs. 1 and 2, may be propelled over the surface of the water by means of oars or paddles of any suitable type. In the present instance I have shown the side floats or cylinders 2 of the craft 1 provided on their upper surfaces, about midway of their length, with loops 13, which form handles whereby the craft 10 may be carried and manipulated and which also are adapted to serve as oar locks through which paddles or oars 14 may be passed and manipulated for use, as shown in Fig. 1. For the purpose of sustaining 15 the wear from the paddles when the latter are manipulated protector strips 15 may be provided and secured to the upper surfaces of the cylinders 2, said strips also sufficiently stiffening the surfaces of the cylinders at 20 such points to avoid any tendency of the cylinders to buckle when the oars are operated and the craft is propelled through the water.

The device as particularly shown in Figs. 25 1 to 4, inclusive, and which is of oblong rectangular form, is designed to provide what I term a two-man boat. This may be of any proper width and of a length to allow 30 a single occupant to sit therein with legs fully extended, as illustrated in Fig. 1, or to allow two persons to be seated, in which event the occupants, one of whom may manipulate the oars, may sit at opposite ends 35 of the craft facing each other and with their legs crossed Turkish-fashion or otherwise arranged so that they may be comfortable and interference with the body movements of the oarsman prevented. A craft of this style may be of such size that, 40 when reversed for use as a bed or lounge, either one or two persons may recline for rest or sleep thereon, or it will serve as a seat cushion to accommodate a number of persons at a time.

45 When the device is deflected it is adapted to collapse into substantially flat form and may then be folded and secured in folded form to enable it to be closely packed and readily carried. For convenience in securing the device in folded condition and carrying it by hand, I preferably provide a carrier-wrapper which is a permanent fixture of the device. This consists of a wrapper strip 16 of suitable form stitched, as indicated at 17, to the upper surface of the bottom 6 on parallel lines lying inwardly of its side edges, leaving the side and end edges of the wrapper free. The two side edges of the wrapper are provided with eyelets 18 for 55 the reception of a lacing cord 19 whereby such edges may be secured together to hold the wrapper confined about the folded and collapsed structure bound therein. Of course, any other suitable means for uniting the side edges may be employed. The

wrapper may be provided at one end with a flap 20 to be turned in between the folds of the body 1 to make the same more compact and secure, and said wrapper is also provided with a hand loop 21 whereby the 70 wrapped structure 1 may be easily and conveniently carried. In the operation of folding the structure 1 it is first folded longitudinally along suitable lines and then rolled or folded transversely upon itself so as to 75 lie substantially within the bounds of the wrapper 16, which is passed around the folded body 1 and secured as previously described.

There may be provided for use in connection with the craft a light-weight slatted platform 22 of a form and size to fit within the frame and upon the bottom 6. This may be of a folding type and arranged to be carried in any convenient manner. Its object 85 is to provide a support on which the occupant, a hunter or fisherman, for example, may stand upright in shooting or fly casting, etc., so as to properly distribute his weight over the bottom 6 and prevent sagging of the latter, thus enabling the occupant to have a firm and secure footing, as will be readily understood.

In Fig. 9 I have shown the embodiment of the invention in what I term a one-man 95 craft, i. e., of such size, when used as a boat, as to accommodate a single occupant. In this embodiment the body 1 is of square or slightly oblong rectangular form and is of the same structure as the two-man craft 100 before described, differing therefrom only in slight details. For instance, with this construction I may use either two or four partitions to divide the floats into a corresponding number of compartments, and the combined 105 hand-loops and oar locks in this one-man craft near one end of the craft for proper arm-reach in manipulating the oars. The occupant sits in this smaller craft with legs crossed and folded and the device is of such 110 size that when reversed it will serve as a short lounge or seat-cushion on which a person may recline and rest or on which one or more persons may comfortably seat themselves.

115 From the foregoing description it will be seen that my invention provides an inflatable and collapsible fabric combination boat and bed or cushion which is simple of construction and may be manufactured and sold at a comparatively low cost, and which may be conveniently handled and transported and is capable of being folded and carried in the hand or upon the person of the user or of being readily and conveniently 120 transported upon an automobile or other vehicle. It is especially adapted for the use of hunters, trappers, fishermen and others, desiring the use of a combined boat and bed 125 which is staunch and safe when afloat, or 130

for use as a pleasure craft and for many other analogous uses. Furthermore, without any change of structure whatever, it provides a convenient couch on which the 5 user may seat himself or recline and rest when desired and on which he may sleep in a comfortable manner.

It will be understood, of course, that I reserve the right to employ the invention for 10 any or all of the purposes described.

Having thus fully described my invention, I claim:

1. A device of the character described comprising an outer rectangular inflatable 15 frame portion composed of permanently connected side cylinders and end cylinders, flexible cone-shaped partitions disposed within said cylinders and sub-dividing the same into air compartments, means for inflating and deflating said compartments, and a flexible bottom surrounded by said cylinders and permanently secured thereto between the upper and lower surfaces thereof.

2. A device of the character described 25 comprising an oblong rectangular inflatable frame structure composed of permanently connected side cylinders and end cylinders, flexible tone shaped partitions centrally subdividing the respective cylinders into separate 30 air compartments, conjointly formed by adjacent halves of adjoining cylinders, means for inflating and deflating the cylinders, and a flexible bottom surrounded by the cylinders and marginally secured to the

inner faces of said cylinders between the 35 upper and lower surfaces thereof.

3. A device of the character described comprising an outer inflatable frame portion and an impervious flexible bottom surrounded thereby and permantly secured to 40 the inner surface thereof, said bottom being arranged between the horizontal center and bottom surface of said frame structure.

4. A device of the character described comprising an inflatable outer frame ar- 45 ranged to surround a central space, a flexible bottom disposed in said central space and secured to the outer frame, and a wrapper secured to said flexible bottom and adapted to be passed about the collapsed 50 and folded structure for securing it in such condition.

5. In a device of the class described, a substantially rectangular foldable frame comprising permanently connected collapsible cylinders open to each other at their ends, collapsible air-tight partitions in each cylinder at a point substantially midway the ends thereof, whereby the said frame includes air-tight compartments including a 55 part of one each of adjoining angularly disposed sides of the frame, means whereby the said compartments may be inflated independent of each other, and a bottom formed of flexible material fitted into said frame 60 and secured at its edges to the sides thereof.

In testimony whereof I affix my signature.
CHARLES F. SMYTH.
